UNITED STATES PATENT OFFICE.

BERNHARD MORVAY, OF VIENNA; AUSTRIA-HUNGARY, ASSIGNOR TO LOUIS HIRSCHFELD, OF NEW YORK, N. Y.

CHAIR AND SOFA BED.

SPECIFICATION forming part of Letters Patent No. 427,597, dated May 13, 1890.

Application filed January 11, 1890. Serial No. 336,647. (No model.) Patented in Austria-Hungary October 17, 1886, No. 18,666 and No. 47,627.

To all whom it may concern:

Be it known that I, BERNHARD MORVAY, of Vienna, in the Empire of Austria, a subject of the Emperor of Austria, have invented certain new and useful Improvements in Chair and Sofa Bed, (for which Letters Patent were granted to me in Austria-Hungary, No. 18,666 and No. 47,627, dated October 17, 1886,) of which the following is a specification.

This invention relates to an improved construction of chair and sofa bed that can be quickly changed from a chair or sofa into a bed, and vice versa; and the invention consists of a chair and sofa bed having a stationary main frame and seat-section, a sliding foot-section that is guided in the main frame and provided with a hinged foot-board, and a vertically-movable auxiliary seat-section which is supported by folding legs that are guided by pivot-links in keepers at the under side of the frame of the auxiliary section. The back of the chair or sofa forms the head-piece and is formed of three hinged sections—a rear section, which forms the head-piece proper, a narrow intermediate connecting-piece, and an upholstered section, which passes over fixed ribs of upright standards at the ends of the chair or sofa frame, so as to form the back, while it serves with the intermediate section to support the head-piece when the chair or sofa is changed into a bed.

In the accompanying drawings, Figures 1 and 2 represent perspective views of my improved chair or sofa bed, showing the same, respectively, in position as a sofa and as a bed; and Figs. 3 and 4 are vertical longitudinal sections showing the sofa-bed, respectively, in position as a bed and as a sofa, the last two figures being drawn on a larger scale.

Similar letters of reference indicate corresponding parts.

Referring to the drawings, A represents the supporting main frame of my improved chair or sofa bed, which frame is provided with a stationary seat-section B and with upright arms or standards C C at the ends of the main frame A. The upright arms C are provided with fixed ribs d d, having curved upper ends

d', which serve for supporting the back D of 50 the chair or sofa bed, which back is formed of three sections—a rear section D', which is pivoted to the supporting-frame A at the rear end of the stationary seat B, a narrow intermediate section D², which is hinged to 55 the upper edge of the rear section D', and an upholstered section D³, which is hinged to the intermediate section D² and which forms the back of the chair or sofa bed proper.

When the sections D' D² D³ are placed in 60 proper position, so as to form the back of the chair or sofa bed, the rear section D' is brought up against the upper edge of the ribs d, the intermediate section D² over the same, and the upholstered section D³ in front of said ribs, 65 as shown clearly in Fig. 4. The back D is by means of the ribs d firmly supported in position by the upright arms C, while when the sections D' D² D³ are swung back of the main frame A clear of the ribs d the rear section D' 70 forms the head-piece and support for the pillow, while the intermediate section D² and upholstered section D³ form the support for the inclined rear section D', as shown clearly in Figs. 2 and 3.

In the lower part of the main frame A, below the stationary seat B, is guided the foot-section E, which latter is provided with side rails e, that are guided in grooves e' of the main frame, as shown in Fig. 3. The foot-section E moves on casters at its front end and has a foot-board E', which is hinged to the front end and which is moved into vertical position when the foot-section E is completely drawn out. A sliding stop-latch f is guided 85 along each side wall of the foot-section E and abuts against the front part of the frame A, so as to retain the foot-section E in position when drawn out, said sliding latches being pushed back by fixed lugs f' at the rear part 90 of the main frame A, as shown in Fig. 4. An auxiliary seat-section E² is supported by lugs g at its under side in keepers g' of the foot-board E, while its opposite end is supported by legs F, which are fulcrumed to lugs h at 95 the under side of the auxiliary seat-frame E², and braced by means of links h', that are pivoted to said legs and guided by pins h³ at their

ends in keepers h^2 at the under side of the auxiliary seat-frame E^2 , as shown clearly in Fig. 3. The inner edge of the auxiliary seat-section E^2 abuts closely against the front edge 5 of the stationary main section B and forms with the same the mattress-section when the chair or sofa is used as a bed. A rug or blanket is placed over the seat-sections, as shown in Fig. 2.

10 When it is desired to change the chair or sofa to a bed, the back is first swung back into the position shown in Figs. 2 and 3, so as to form the head-piece of the bed. The foot-section is then moved forward until stopped 15 by the latches f . The foot-board E' is then moved in upright position against the stationary front wall of the frame of the foot-section E. The auxiliary seat-section E^2 is then lifted, so as to be supported by the legs 20 F and by its front lugs in the keepers of the foot-board, whereby the seat-section E^2 is firmly supported on the foot-section. The legs extend through openings in the bottom of the foot-section E and rest on the floor. For 25 changing the bed into a sofa or chair the seat-section is first removed and the foot-board lowered, the auxiliary seat-section being placed in position on the foot-board and then pushed back with the foot-section into the 30 main frame A, as shown in Fig. 4, after which the sections composing the head-piece are returned, so as to form the back of the chair or sofa. In this manner an arm-chair can be readily changed into a single bed or a sofa 35 into a double bed, and vice versa, whenever required.

Having thus described my invention, I claim as new and desire to secure by Letters Patent—

40 1. The combination, with a main frame having a stationary seat-section, of upright stand-

ards at the end of the main frame provided with raised ribs, and a back-section formed of three parts—a rear section pivoted to the rear part of the main frame, an intermediate 45 section hinged to the rear section, and an upholstered section hinged to the intermediate section, said sections being adapted to be moved over the ribs of the standards, so as to form the back of the sofa or chair, or into a 50 position back of the main frame, so as to form the head-piece, substantially as set forth.

2. The combination, with a main frame having a stationary seat-section, of a foot-section guided in said main frame, means for stopping 55 the foot-section when moved either outwardly or inwardly in said main frame, a foot-board hinged to said foot-section, an auxiliary seat-section supported on keepers on the foot-board, and folding legs applied to the 60 inner end of the auxiliary seat-section, substantially as set forth.

3. The combination, with a main frame having a stationary seat-section, of a foot-section guided in said main frame, means for stopping 65 said foot-section when moved inwardly or outwardly from said main frame, a foot-board hinged to the foot-section, an auxiliary seat-section provided with lugs supported in keepers on the foot-board, and pivoted and folding legs at the inner end of the auxiliary seat-section, said legs being connected by pivoted 70 and sliding braces, with keepers at the under side of the auxiliary seat-section, substantially as set forth.

In testimony that I claim the foregoing as my invention I have signed my name in presence of two subscribing witnesses.

BERNHARD MORVAY.
